Attorney

UNITED STATES PATENT OFFICE.

JAMES BALL, OF LOUISA, KENTUCKY

GAS-BURNER.

No. 873,485.

Specification of Letters Patent.

Patented Dec. 10, 1907.

Application filed March 31, 1906. Serial No. 309,146.

To all whom it may concern:

Be it known that I, JAMES BALL, a citizen of the United States, residing at Louisa, in the county of Lawrence and State of Kentucky, have invented certain new and useful Improvements in Gas-Burners, of which the following is a specification.

This invention relates to gas burners and the object of the invention is to provide a simple, economical and effective gas burner by means of which an exceptionally hot flame is obtained through a novel arrangement of inlet and outlet openings, whereby the gas and air are thoroughly mixed preparatory to the escape of the mixture, and the merging of the escaping jets of the mixture is insured, the same being productive of a more thorough combustion of the mixture and incidentally a hotter and more satisfactory flame.

With the above general object in view, the invention consists in the novel construction, combination and arrangement of parts hereinafter more fully described, illustrated and claimed.

In the accompanying drawings, Figure 1 is a vertical section through a burner embodying the present invention. Fig. 2 is a plan view of the same.

The burner comprises essentially a mixing chamber 1 which, in the preferred embodiment of this invention, is in the form of a cone, as shown in Fig. 1, the same being provided at intervals around its outer side with air inlet openings 2 of considerable size. Extending downward from the bottom 3 of the mixing chamber is a gas inlet nozzle 4 which is threaded, as shown at 5, to adapt the same to be connected to a service or supply pipe. At its opposite or upper end, the conical mixing chamber is provided with an upstanding nozzle or neck 6 which fits into a tubular boss or entrance nozzle 7 arranged centrally of a distributing chamber 8 and extending downward from the bottom thereof, as clearly shown in Fig. 1, the parts 6 and 7 being detachably connected together by means of a set screw 9.

The distributing chamber 8 of the burner may be of any desired form, being shown as of oblong and substantially rectangular shape in plan and closed at all points with the exception of a multiplicity of outlet ports 10 in the upper side thereof. These ports are quite small and are bored at an inclination. It will be observed by reference to Fig. 1 that some of the ports are inclined in one direction and the rest in the other direction. These ports are so arranged that those which lie next to each other incline in opposite directions or slant obliquely upward toward each other, thereby causing the jets of mixture passing outward and upward there-through to merge or combine and intermingle just above the upper surface of the burner which has the effect of a more thorough mixing of the gas immediately upon its escape from the distributing chamber and obtaining thereby a more thorough combustion and consequently a flame of greater heating capacity.

I claim:

A gas burner comprising a cone-shaped mixing chamber with a series of openings arranged at suitable distances apart around its surrounding wall, the bottom of the chamber having a depending screw threaded nozzle, a neck formed by a continuation of the upper end of the cone, a flat top distributing chamber having a single row of inclined outlet openings arranged on opposite sides of its top portion, said openings being constructed in pairs and arranged at suitable distances apart, and said distributing chamber having a central nozzle serving to be slidably mounted on said neck and a set screw for detachably securing the nozzle to said neck, substantially as specified.

In testimony whereof I affix my signature in presence of two witnesses.

JAMES BALL.
